BUTTON COMPANY, OF WATERBURY, CONNECTICUT, A CORPORATION OF CON-
NECTICUT.

ESCAPEMENT FOR BUTTON-ATTACHING MACHINES.

1,157,743.

Specification of Letters Patent.

Patented Oct. 26, 1915.

Application filed June 4, 1915. Serial No. 32,197.

To all whom it may concern:

Be it known that I, FRANKLIN R. WHITE, a citizen of the United States, and a resident of Waterbury, in the county of New Haven and State of Connecticut, have made and invented certain new and useful Improvements in Escapements for Button-Attaching Machines, of which the following is a specification.

10 This invention relates to a button escapement for button attaching machines.

An object of the present invention is to provide a button escapement which may be used with buttons of different sizes, *i. e.*, 15 it may be used for successively and singly releasing buttons of either the one or two-piece type.

A further object is to provide a button escapement of such design and arrangement 20 that a single button may be released when so desired, and without in any way interfering with the automatic operation of the escapement.

It often happens that an operator, while 25 using a button attaching machine, will accidentally dislodge the button from above the button attaching anvil, and it is customary, in such event, for the operator to remove the corresponding fastener from its 30 seated position upon the anvil of the machine. This is a dangerous practice, and often results in severe injury to the operator, as there is considerable danger of the foot treadle being accidentally or unconsciously depressed during such procedure. 35 In order to do away with this practice, the button escapement is so arranged that it may be quickly and manually oscillated, resulting in the releasement of a single button which immediately assumes the position, 40 and takes the place, of that which was accidentally dislodged, thus saving considerable time and labor, and eliminating a dangerous practice, as well as preventing the waste of 45 the tacks or fasteners.

Other objects and advantages will appear as the description proceeds, wherein it is to be understood that changes in the precise embodiment of the invention can be made 50 within the scope of what is claimed, without departing from the spirit thereof.

The preferred embodiment of my inven-

tion is disclosed in the accompanying drawings, wherein:—

Figure 1 is a fragmental view in front 55 elevation of a button attaching machine, the same being equipped with a button escapement embodying the characteristic features of my invention; Fig. 2 is a top plan view of a portion of the button chute, and including the button escapement, and illustrating the same subsequent to the release- 60 ment of a button; Fig. 3 is a similar view and illustrating the escapement in its normal position; Fig. 4 is a sectional view 65 taken on the line 4—4 of Fig. 2; Fig. 5 is a fragmental view in vertical section of the chute and adjacent portions of the escape- 70 ment, and illustrating the manner in which the single-piece buttons are adapted to pass beneath the admission jaw of the escape- 75 ment, the admission jaw being in its lowered position; Fig. 6 is a similar view with the admission jaw in its raised position, preventing the wedging of the two-piece but- tons should they ride one over the other as illustrated in the said figure.

Referring specifically to the several views, the button machine 10 includes the usual button hopper 11 and button chute 12, the latter terminating at the button receiving members 13, to which it is adapted to deliver buttons. A plunger 14 is mounted above the button receiving members and is connected to, so as to be operated by, the 80 actuating lever 14', the movements of the plunger resulting in the securing of the tack or fastener to the button and the application of the same to the desired article.

The button chute 12 is provided upon its 85 under surface, and approximately midway of its length, with the recess 15, in which is rigidly secured a pivot pin 16. A button escapement 17 is mounted for oscillation upon the pivot pin 16, and includes a frame 90 18 which projects beneath, and across, the button chute, and terminates in the spaced sides 19 which embrace the button chute therebetween. Mounted upon the sides 19 of the frame, are the jaws or stop members 1 20, which extend across the runway 21 of the chute and are adapted to singly and successively release the buttons contained within the upper portion of the chute. The sides

of the chute are cut away as at 22, for the reception of the oscillating jaws 20, so that they are adapted to contact with the upwardly projecting hub of the button, and singly release the same. The lower of the jaws 20, and which constitutes the releasing member 23, is rigidly and fixedly secured to, so as to form a part of, the side 19 of the frame. The upper jaw forms a selecting or admission member 24, and is adjustably secured to the side 19 so as to move away from, or toward, the bottom of the chute runway 21, this adjustable securing of the admission member being effected by the provision of the pin 25 upon the side 19, and which projects within a recess 26 formed in the admission member, and a second pin 27 which is fixedly secured to the admission member and projects through and beyond an opening 28 formed in the side 19. A fastening screw 29 extends within the side 19 of the frame and is adapted to contact with the pin 27 and fixedly hold the admission member in its adjusted position.

25 With the releasing jaws thus arranged, the escapement is adapted to effectively release buttons of either the one or two-piece type, the heads of which buttons vary in thickness. With the admission jaw in position 30 close to the bottom of the runway 21, the one-piece button which is characterized by thin heads and small or short hubs, can be successfully released.

When it is desired to use two-piece buttons, the hubs of which are larger, and the heads of which are thicker, than the one-piece button of the same diameter, the previously mentioned adjustment of the admission member or jaw 24 results in the 35 choking or clogging of the button escapement, due to the fact that as the head of one button rides over the head of the lower and adjacent button, the head of the upper button is forced into wedged contact with the 40 lower or under surface of the admission member, and the forced oscillation of the escapement does not always result in the release of a button, and in machines of the present type it is absolutely essential 45 that the machine operate successfully, each and every time. In order, therefore, to accommodate for the slightly raised or elevated position of the overriding button, the admission member 24 is elevated, or moved 50 away from the bottom of the runway of the chute, and is securely locked in such position, as illustrated in Fig. 6, by the set screw 29, the button escapement being thus adaptable for buttons of different styles or types, and 55 operating with equal effectiveness with each.

The button escapement is automatically oscillated by the actuating lever 14', which is mechanically and positively connected to the moving mechanism of the entire machine. The actuating lever is preferably 60

equipped with a striking block 30, which is arranged to contact with a pivotally mounted buffering plate 31, carried by the escapement frame 18. This buffering plate is provided with the upper beveled edge 32 against which the striking block 30 is adapted to contact, so that as the actuating lever is raised and lowered, the escapement will be forcibly moved in one direction, resulting in the withdrawal of the admission member 70 from above the runway 21, and the entrance of a button within the escapement. The return motion of the escapement is accomplished by the action of the spring 33, which is secured to the escapement frame 18 and 75 the chute 12, and so located that the tension of the spring forcibly oscillates the button escapement in a direction opposite to that produced by the contact of the striking block with the buffering plate 31. Thus for 80 each complete oscillation of the actuating lever, the button escapement will perform a complete oscillation, resulting in the release of a single button.

The buffering plate 31 which is pivotally secured to the side 19 of the escapement frame, is substantially triangular in cross-section, so that it may rock with respect to the frame, and is constrained in such movements by the tension spring 34, the same extending between a knob or projection 35 upon the buffering plate, and a similar projection 36 carried by the escapement frame. The spring is so arranged that the end 37 of the buffering plate which is provided with the 90 beveled edge 32 and against which the striking block is adapted to contact, is resiliently held away from the frame 18, and the spring is of sufficient strength to maintain the buffering plate so located during the forced oscillation of the button escapement, the spring 34 being considerably heavier than the spring 33. The buffering plate thus acts as a cushion against which the striking block contacts, and thus prevents the severe hammering action otherwise experienced. The normal position of the parts of the button escapement is disclosed in Fig. 3, and the button contained within the escapement may be released by striking the escapement frame 100 so as to force the releasing jaw 23 from above the chute runway 21, the button escapement being allowed to so oscillate by means of the pivotal mounting of the buffering plate 31, which, although already in 105 contact with the then stationary striking block 30, allows the escapement frame to rock and move with relation thereto. In addition, therefore, to the ordinary automatic operation of the button escapement 110 115 so as to force the releasing jaw 23 from above the chute runway 21, the button escapement being allowed to so oscillate by means of the pivotal mounting of the buffering plate 31, which, although already in contact with the then stationary striking block 30, allows the escapement frame to rock and move with relation thereto. In addition, therefore, to the ordinary automatic operation of the button escapement 120 125 so as to force the releasing jaw 23 from above the chute runway 21, the button escapement being allowed to so oscillate by means of the pivotal mounting of the buffering plate 31, which, although already in contact with the then stationary striking block 30, allows the escapement frame to rock and move with relation thereto. In addition, therefore, to the ordinary automatic operation of the button escapement 130

should a button become accidentally dislodged therefrom.

What I claim is:—

1. An escapement for use in connection with a chute comprising spaced jaws mounted for movement with respect to said chute, and one of said jaws mounted for adjustment toward and away from the bottom of the chute runway. 65
  2. An escapement for chutes comprising a frame mounted for movement with respect to said chute, and jaws carried by said frame and projecting above, and transversely of, the chute runway, one of said jaws mounted for adjustment toward and away from the bottom wall of said runway. 70
  3. An escapement for a chute comprising a frame, means for mounting the same to oscillate with respect to said chute, means carried by said frame adapted to singly release the contents of said chute, said means adjustable in a direction perpendicular to the bottom wall of the runway of said chute, and means for holding the same in adjusted 75 position. 80
  4. A button escapement for a button chute comprising a frame mounted for movement with respect to said chute, and jaws carried by said frame and projecting above, and transversely of, the runway of said chute, the upper or foremost jaw being mounted for adjustment toward and away from the bottom of said runway. 85
  5. An escapement for chutes comprising a frame mounted for movement with respect to said chute, admission and releasing members carried by said frame and projecting above the runway of said chute, the admission member being mounted for adjustment 90 in a direction perpendicular to the bottom wall of the runway of said chute, and means for holding it in adjusted position. 95
  6. A button escapement for a button chute comprising a frame pivotally secured to said chute and adapted to oscillate with respect therewith, said frame including upstanding sides embracing said chute therebetween, and admission and releasing members carried by said frame projecting transversely 100 of said runway, said admission member mounted for adjustment in a direction perpendicular to the bottom wall of said runway. 105
  7. A button escapement for button chutes comprising a frame mounted to oscillate with respect to said chute, said frame including upstanding and spaced sides embracing said chute therebetween, and admission and releasing members carried by 110 said sides, projecting transversely of said
- runway, and adapted to singly release articles disposed therein, said admission member adjustably secured to said frame so that it may be adjusted toward and away from the bottom wall of said runway. 65
8. A mechanism of the class described comprising an escapement, and a buffing member movably carried thereby. 70
9. An escapement comprising releasing members, and a buffing member carried thereby and movable with respect thereto. 75
10. In combination, a chute, an escapement therefor, and a buffing member movably carried by said escapement. 80
11. An escapement for a chute comprising means for releasing articles disposed within the runway of said chute, and a buffing member carried by said means and mounted for resilient movement with respect thereto. 85
12. A button escapement for a chute comprising button releasing means movable with respect to said chute, and a buffing member carried by said means and movable with respect thereto and resiliently resisting such motion. 90
13. An escapement provided with a buffing member, said buffing member adapted to rock with respect thereto, and a spring engaging said buffing member and said escapement and resiliently holding the same against rocking. 95
14. A mechanism of the class described comprising a chute, an escapement mechanism adapted to oscillate with respect thereto, resilient means engaging said escapement adapted to oscillate the same in one direction, a buffing plate carried by said escapement and mounted for resilient motion with respect thereto, and means adapted to contact with said buffing plate for the forced 100 oscillation of said escapement. 100
15. A mechanism of the class described comprising a chute, an escapement mechanism adapted to oscillate with respect thereto, resilient means engaging said escapement adapted to oscillate the same in one direction, a buffing plate carried by said escapement and mounted for resilient motion with respect thereto, and means adapted to contact with said buffing plate for the forced 110 oscillation of said escapement, said means normally in contact with said buffing plate. 110

Signed at Waterbury, in the county of New Haven and State of Connecticut this 28th day of May A. D. 1915.
